UNITED STATES PATENT OFFICE.

ALFRED WOLFF, OF BERLIN, GERMANY.

BREECH FOR FIRING DEVICES OF ALL KINDS, PARTICULARLY ADAPTED FOR SHELL MORTARS.

Application filed July 30, 1920. Serial No. 400,259.

To all whom it may concern:

Be it known that I, ALFRED WOLFF, citizen of Germany, and resident of Berlin, have invented a new and useful Breech for Firing Devices of All Kinds, Particularly Adapted for Shell Mortars (for which I have filed applications in Germany, February 17, 1916, and January 7, 1916; Spain, January 23, 1920; Austria, March 17, 1916, 5 and November 10, 1917; Hungary, March 21, 1916; Switzerland, January 3, 1920; Netherlands, December 27, 1917, and December 28, 1917, and Sweden, March 26, 1918), of which the following is a specification.

15 The present invention relates to a breech for firing devices of all kinds, and is in particular adapted for shell-mortars.

The feature of the present invention consists in that the same member is employed 20 for cocking and securing, or releasing for operation, respectively, the firing device, a signal bolt being provided, which by its position will indicate whether the firing device is cocked or not, and that the device is 25 fired by aid of a member which is movable in all directions, so that it may be operated from any side and with equal advantage.

Compared to similar devices heretofore disclosed which all possessed a separate cocking and a separate securing device, the device according to the present invention embodies a number of particular advantages. 30 Owing to the greatly simplified manipulation, as only one operation is required for 35 cocking and securing, the firing speed of the device is considerably increased and at the same time the greatest reliability in working is obtained, as, in case the cocked device should go off unintentionally the percussion bolt can never act with its full force, 40 but only relatively to the gradually yielding securing device. Furthermore the fact that the cocking and securing device is arranged at the side, a number of further advantages is secured, as it allows of a better 45 cover of the crew of the mortar.

The accompanying drawing is a sectional view of an apparatus constructed in accordance with my invention.

50 In this drawing *a* is the wall of the mortar, within which the percussion bolt *c* with its bar *c'* is movable in known manner under action of a spring *b*. The cocking and securing, or releasing for operation of the 55 percussion bolt or firing pin is effected by the

eccentric bolt *d* which is operated from outside by the throwing over of a lever *e*. On the said eccentric bolt *d* is provided a shoulder *d'* which in the position shown by full lines engaged with the shoulder *c²* of the percussion bolt or firing pin indicates the cocked and secured position of the percussion bolt, whereas the dotted lines indicate the position of the shoulder *d'* in cocked and released position of the percussion bolt *c*, or the bar *c'*, respectively. The lever *e* engages in both its terminal positions against stop lugs *f*, *f'* preferably with a light spring.

In a bore of the eccentric bolt *d* is fitted a signal bolt *g* which is placed under action 70 of a spring *i*. The arrangement is such, that when the firing pin is cocked the signal bolt does not project from the bolt *d*, but that when the firing pin is released, by the bar *l*, the spring *b* projects the firing pin *c* and 75 the shoulder *c²* will strike the cam face of the head *h* and thereby project the signal bolt.

By means of the bar *l*, which may be engaged with a shoulder *c³* of the firing pin and on which acts a spring *m*, the trigger *k* 80 may be coupled to the firing pin *c*, to hold the latter in cocked position, the bar *l* being connected by means of bolt *n* or in a similar manner with the trigger *k*, for universal rocking movement of the trigger 85 and the latter being held by the same arrangement only, and without further means to the mortar.

The firing is effected in any suitable manner by hand, by means of a rope fastened 90 into hole *o* or other means, and as the trigger can move in either direction; it may also be effected from either side.

The position shown in the drawing shows the device in a cocked position. By moving the trigger *k* from the position shown, the bar *l* is lifted off and will then, under action of spring *b* release the bolt *c*.

Should the pin *c* be released by the bolt *l*, while the cocking lever *e* is in the full line 100 position, said pin will cam said lever around to dotted line position and in so doing, said pin will be retarded. Hence unintentional firing is prevented.

The arrangement shown and described in 105 the foregoing specification may be modified in details without departing from the idea of the invention.

Claims.

1. In ordnance, a breech, a firing pin there- 110

in, a spring to project the firing pin; a trigger, a bolt carried thereby to engage and hold the firing pin in cocked position, an eccentric bolt mounted for partial rotation in the breech and arranged to move the firing pin to cocked position when said eccentric bolt is turned in one direction, and a spring retracted signal bolt arranged in the bore of the eccentric bolt and projected by the firing pin when the latter is projected to firing position.

2. In ordnance, a breech, a spring projected firing pin having a pair of shoulders, a trigger having means to engage one of said shoulders and hold the firing pin in cocked position, an eccentric bolt mounted for partial rotation and having means to

engage the other shoulder of the firing pin to move the latter to cocked position when said eccentric bolt is turned in one direction, and a spring retracted signal bolt arranged in the bore of the eccentric bolt and having a beveled head for engagement by the last named shoulder of the firing pin to cause said signal bolt to be projected when the firing pin is projected by its spring to firing position. 20 25

In testimony whereof I affix my signature in presence of two witnesses.

ALFRED WOLFF.
